UNITED STATES PATENT OFFICE.

ROBERT T. PEIRCE, OF NEWPORT NEWS, VIRGINIA.

DOOR OR GATE LATCH.

1,108,783.

Specification of Letters Patent.

Patented Aug. 25, 1914.

Application filed September 23, 1913. Serial No. 791,420.

To all whom it may concern:

Be it known that I, ROBERT T. PEIRCE, a citizen of the United States, residing at Newport News, in the county of Warwick 5 and State of Virginia, have invented certain new and useful Improvements in Door or Gate Latches, of which the following is a specification.

This invention relates to door or gate 10 latches and has for its primary object to provide a novel device which will automatically operate while the door is being closed, so as to allow for the closing of the door but preventing the opening of the same unless 15 the latch is released.

Another object of the invention resides in the provision of a device of this character which may be manufactured at a minimum cost, being formed from a single sheet 20 of metal which may be stamped or pressed as desired, having the ends thereof so formed as to automatically operate the device when the same comes in contact with the door, the latch being pivotally mounted on the 25 door jamb.

Other objects as well as the nature, characteristic features and scope of my invention will be more readily understood from the following description taken in connection 30 with the accompanying drawings and pointed out in the claims forming a part of this specification.

Referring to the drawings:—Figure 1 is an elevation of my improved device illustrating 35 the application thereof; Fig. 2 is a plan view of the latch; Fig. 3 is a longitudinal sectional view; Fig. 4 is a cross sectional view taken on the line 4—4 of Fig. 2; Fig. 5 is a perspective view of the device 40 showing to advantage the reinforcing strip which is formed midway the ends thereof; Fig. 6 is a detail fragmentary view of a modified form; and Fig. 7 is a similar view of another form.

45 In the drawings wherein is illustrated the preferred embodiment of this invention, in order to properly illustrate the application thereof, a portion of a door jamb 5 is provided which has associated therewith, a portion 50 of a door or gate 6. Pivotally mounted on the door jamb approximately midway its marginal side is my improved latch 7.

55 The latch comprises a sheet or strap of metal which is stamped, cast or pressed, having the opposite ends 8 thereof turned in angled relation to the body so as to pro-

vide a structure substantially triangular in plan as shown to advantage in Figs. 2 and 3. The angled portions 9 of the latch are preferably pointed so as to facilitate the actuating of the device on its pivot point 10 when pressure is exerted on one of the ends 8, by the door or the like, so as to throw the same in a position as indicated by the dotted lines in Fig. 1. The upper marginal side 60 of the latch is extended as indicated at 11 and bent into right angled relation with the body thereof so as to provide a reinforcing element. An aperture 12 is formed intermediate the ends 8 and is adapted for engagement 65 with the pivot pin 10. The aperture 12 is formed slightly above the center of gravity in order to normally hold the latch in a horizontal position on the pivot pin 10 as advantageously illustrated in 70 Fig. 1.

In view of the fact that the side of the door 6 is constantly contacting with one of the ends 8 of the latch, it may be desired to use a reinforcing element between each of 80 said ends 8 and the body portion so as to eliminate the displacement of the ends. In Fig. 6 is illustrated a form which will overcome this defect should it be found necessary namely by providing a web portion 13 85 in the angle between the body portion and the ends 8, which merely comprises an enlargement as advantageously illustrated in this figure. A still further means for preventing the displacement of the ends 8 is 90 shown to advantage in Fig. 7 which comprises a flat spring 14 which is preferably arched and has the opposite ends thereof fixedly secured to the ends 8 and the body portion of the latch through the medium of 95 rivets 15. By mounting the flat springs 14 between the ends 8 and the body of the strap, that possibility of displacement of the ends 8 will be reduced to a minimum, since the springs will serve as reinforcing 100 elements to maintain ends 8 in their normally inclined position thereby withstand ing the strain which is exerted thereon when the door 6 comes in contact therewith.

In the manufacture of these devices, the 105 same may be either stamped, cast or pressed from a sheet of metal, as above pointed out having the ends thereof turned in angled relation to the body, and the reinforcing strip 11 arranged on the upper marginal 110 edge of the body portion intermediate the ends thereof. The aperture 12 through

which is engaged the pivot pin 10, is formed in the body portion of the latch approximately midway the ends of said body and intermediate its longitudinal edges, and is of a diameter slightly larger than that of the outer periphery of the pin 10 so as to allow for the free rotation thereof when pressure is exerted on the inclined sides 8 by the door or gate 6. It is readily seen that when the latch is thrown in a position as indicated by the dotted lines in Fig. 1, due to the contacting of the door or gate 6 therewith, that as soon as the said door has reached the plane of the door jamb 5, that the latch will immediately swing into its normal position, for preventing the opening of the door or gate, unless the latch is swung beyond the door as is obvious.

It will be understood that the above description and accompanying drawings comprehend only the general and preferred embodiment of my invention and that various minor changes in details of construction, proportion and arrangement of parts, may be made within the scope of the appended claims and without sacrificing any of the advantages of my invention.

Having thus fully described my invention, what I claim as new and desire to secure by Letters Patent is:—

1. A door latch including a metallic strap

for pivotal engagement with a door jamb, the opposite ends of which are bent at acute angles toward each other to provide inclined door engaging surfaces, said strap 35 normally lying transversely of the door, whereby to automatically actuate the same when the door contacts therewith and automatically assuming its normal position after the door is closed for locking the same, and a reinforcing means associated with the opposite ends of said strap substantially as specified.

2. A door latch including a metallic strap for pivotal engagement with a door jamb, 15 the opposite ends of which are bent at acute angles to the body to provide inclined door engaging surfaces, one of the marginal sides having a portion extended therefrom to provide a reinforcing portion, said latch being automatically actuated when the door contacts therewith to permit of the closing of the door and immediately automatically assuming its normal position for locking the door.

In testimony whereof I affix my signature in presence of two witnesses.

ROBERT T. PEIRCE.
